UNITED STATES PATENT OFFICE.

JOHN A. PILCHER, OF ROANOKE, VIRGINIA.

RAILWAY CAR AND TRUCK CONSTRUCTION.

1,406,076.

Specification of Letters Patent.

Patented Feb. 7, 1922.

Application filed May 17, 1920. Serial No. 381,835.

To all whom it may concern:

Be it known that I, JOHN A. PILCHER, a citizen of the United States, residing at Roanoke, in the county of Roanoke and State of Virginia, have invented certain new and useful Improvements in Railway Car and Truck Construction, of which the following is a specification.

This invention relates to trucks for railway vehicles or the like and has for its principal object to provide an improved method of carrying the load of the car body. Another object is to provide improvements in the detail form and arrangement of truck members whereby the loads may be properly equalized, while at the same time the forces will be carried by the truck parts in a direct manner and with the expenditure of a reduced amount of metal. Other objects will hereinafter appear.

The invention consists of the formation, combination and arrangement of parts as will be shown and described, and particularly as will be set forth in the appended claims.

In the drawings which form a part of the present application, and which show a preferred embodiment of the invention, Figure 1 is a plan view of a locomotive tender having two trucks arranged in accordance with the present invention. Figure 2 is a side elevational view of the same. Figure 3 is a plan view of a slightly modified arrangement of the same system of support. Figure 4 is a diagrammatic view, in side elevation, of the lower portion of a tender, indicating the displacement of the trucks under certain track conditions. Figure 5 is a transverse vertical section taken through the tender and truck, approximately on the line B—B of Figure 2. Figure 6 is a broken sectional view of the tender and truck, this view being taken substantially on the line C—C of Figure 2. Figure 7 is a vertical sectional view taken on the line A—A through the center trunnion between the tender and a truck. Figure 8 is a fragmentary view taken in section on the line D—D of Figure 3 and showing the arrangement of rockers in the modified arrangement of Figure 3. Figures 9, 10 and 11 are fragmentary views, in vertical cross section, showing two methods of construction for the equalizing bolster of the tender. Figure 12 is a partial plan view of one of the trucks, Figure 13 a side elevational view of the same. Figure 14 is an end

elevational view, partly in section, of the same truck, the sectioned portion being taken approximately on the line E—E of Figure 12. Figure 15 is a slightly enlarged 60 side elevational view of a portion of the two co-acting truck side frames together with various of the cooperating equalizing members employed therewith. Figures 16, 17, 18 and 19 are vertical sectional views 65 taken through the side frames and equalizing members on the lines F—F, G—G, H—H and J—J respectively, Figure 15. Figure 20 is an end elevational view of one of the equalizer struts, Figure 21 a side elevational 70 view of the central equalizer lever, Figure 22 an end elevational view of one of the spring seats and Figure 23 a side elevational view of one of the spring seat equalizers.

Referring now to these drawings, the body 75 of the car or tender is indicated by the numeral 50. Secured beneath this is the center sill 51, which is formed of a suitable section such as a single I-beam as in Figures 5, 6, 7, 9 and 10, or of a pair of channels as 80 in Figures 8 and 11. The tender is supported upon two trucks, the front end truck being marked "Front" and the rear end one being marked "Rear" in Figure 2 for reference. The weight of the tender is applied 85 to the rear truck at four points, 52, 53, 54 and 55, and to the front truck at three points, 56, 57 and 58, Figure 1. In the modification shown in Figure 3 the rear truck as before has four supporting points 52, 53, 54 90 and 55, and the load is carried by the front truck at three points, 59, 60 and 61.

The invention has to do primarily with such a method of supporting the load of railway vehicles where there are load carrying points upon each truck at spaced distances, longitudinally of the truck. The four point arrangement of the rear truck is of a simple type with all of the bearing points in a common horizontal plane, and 100 with no provision for relative displacement or adjustment of one bearing point with respect to the general plane. It would be desirable to have the same simple arrangement for the other truck, but when entering or 105 leaving a curve it is necessary that the tender or car body assume a certain warped position because of the gradual elevation of the center rail to attain the full super-elevation by the time the full degree of curvature is reached. If now the tender should 110 be supported at each end upon four unad-

2

justing points in a plane, it will be seen that a decided inequality of loading would result because of the greater super-elevation of the rail at the front truck than at the rear truck.

5 In open top cars such as gondolas and hoppers, the car body does not offer a high resistance to the torsion necessary to prevent such unequal loadings, but in a closed top car such as a tender it is difficult to warp the body sufficiently to allow such a method of support. Accordingly the present invention includes as one of its especial features the provision for use of such a plain, four point truck arrangement at one end of the vehicle

10 15 and a three point supporting arrangement at the other end. The three-point support at the one end responds to any change of plane, just as a three legged stool will always fit to any irregularity of surface.

20 The details of this portion of the construction can be best seen in Figures 5 to 11. The cross section of Figure 6 shows the supporting on the front truck at the points 56 and 57 of Figure 1 or 59 and 60 of Figure 3. The identical construction may be used for the rear truck at the points 52 and 54 or 53 and 55. In this construction, roller seats 62 are affixed at suitable points to the body of the tender immediately over co-operating

25 30 seats 63 on the detachable trucks. Rollers or rockers 64 are interposed between these seats and these are arranged in radial fashion to permit the trucks to swivel under the tender about the central swivel points 65.

35 At the front end of the front truck there are provided the same bottom roller seats 63 and rollers 64, but the top roller seats 66 shown in Figure 5 are not secured directly and rigidly to the tender floor but are carried

40 45 at the ends of a cross equalizer 67, which in turn receives the load of the tender at the central sill, at 68, in Figure 5. This equalizer surrounds the center sill and has a bottom tie member 69 which passes beneath the same. A broken detail of this tie construction is shown in Figure 9. The loading point 68 may be constructed in a variety of ways. In Figure 5 ball-shaped bearings are secured to opposite sides of the center

50 55 sill web, near the top of the sill, and the companion halves of the equalizer 67 are provided with sockets for co-operating in a rocking fashion with these bearings. In Figure 10 the sockets are shown as affixed to the sill and the ball-shaped bearings as formed on the ends of the equalizer halves. In this figure also the bottom tie member 69 of the equalizer is shown of link and pin construction instead of the riveted tension

60 65 member of Figures 5 and 9. In Figure 11 the same construction is shown as adapted to channel center sills instead of I-beam sills as in the preceding forms of this construction. While these several modifications in equalizer construction are shown, yet they

all have the one point in common; that the load is applied to one point and that the superimposed tender may rock laterally, at least within limits, upon the equalizer. In Figure 3 the equalizer is omitted and the 70 load from the point 61 is applied directly to the truck at this central point. In this construction rollers 69 of the same type as used at the other points are inserted directly between a top roller seat 70 and the bottom 75 roller seat 71. The seat 70 is attached to the center sills as at 51 and the seat 71 is formed at the center of the truck cross bolster 72. The three sets of rollers in this construction allow the truck to swivel about the center 65 and at the same time prevent pinching and binding from the warp of the tender when entering or leaving a curve.

It is of importance that such a system of loading be carried upon trucks which are 85 fully equalized, so that one wheel of a truck can never be loaded more than the others from the local warping of the tender. To this end the trucks are constructed in accordance with the principles of equalization 90 set forth in the Hankins Patent, #1,241,375 of Sept. 25, 1917. In the present use of this truck there is a possibility of movement of one spring seat 68 out of the general plane of these seats, hence the central portion of 95 the truck bolster is formed of a steel plate 73. This carries at its center the female portion 74 of the trunnion 65, there being a local stiffening member 75 secured beneath this plate and the member 74. The load 100 from the tender is applied to the truck cross bolsters 76 at the aforesaid roller seats 63, the plate 73 extending between these cross bolsters and being secured thereto at 77, the plate 73 thus holding the entire truck 105 square but yet allowing a limited relative vertical displacement of the roller seats 63. The ends of the cross bolsters 76 are carried upon bolster springs 78, which are here shown as of elliptic form.

110 The side frame equalization follow the Hankins principles from this point on although some special features of construction have been introduced to adapt this truck to the particular use. The truck side frames at 115 each side of the truck are made in two sections, 79 and 80, the first of these carrying the one end oil box 81 and the second the other end oil box 82 and the middle oil box 83, the trucks being of the six wheel type. 120 Tie bars 84 extend from the oil boxes to the side frames. The side frame, or section, 79, is hinged to the frame 80 over the middle oil box at 85. Each of the side frames has a window opening for accommodating an 125 end of one of the cross bolsters 76 and a spring 78. This window opening is defined upon one side by the truss tie member 86 and at the other side by the guide member 87. Each of these members is formed to guide 130

the bolster and spring in its vertical movement.

The springs 78 are carried by a spring seat 88 which is slidably disposed in the 5 window opening and has guide flanges 89 for cooperation with the guide faces of the frame members 86 and 87.

The spring seat 88 has its lower extremity 90 formed as a rocker or roller and this is 10 seated in a cooperatively formed seat in the end of a frame lever 91, the spring seat thus being capable of some slight rotation upon the lever 91. The lever 91 is seated between its extremities, at 92 in sockets formed upon 15 the side frame so that it may fulcrum about this point as a center. The upward reaction of the inner end of this lever from the spring load is received by a strut 93 which also is arranged to have a slight rocking 20 motion upon the lever 91. The upper end of the strut 93 reacts upon the bearing at this point also being arranged for a slight pivotal movement. The strut 93 is not attached to either the lever 91 or the lever 94 but is 25 simply set in position between them, the load always tending to keep the strut in position and there being suitable pockets provided to prevent accidental displacement of the parts should the load be removed. 30 A similar series of levers and strut is provided for each of the side frames 79 and 80 so that the load of the tender puts an upward force into each end of the lever 94 through a strut 93. This lever is attached 35 in pivoted fashion to the side frame 80 at the trunnion point 85 between the two frames. In order to provide this two-fold pivot the inner end 95 of frame 80 is made of box section with an open end into which the end 40 96 of frame 79 extends. This end of frame 79 is made of rocker shape and seats in a cooperatively formed pocket 97 in the lower, inner face of the said box section. Cast out from each side of the boxed end of frame 45 80 is a cylindrical bearing 98. The lever 94 is made of two parts, one being positioned along each side of the boxed end 95 and upon a bearing 98.

The lower end 99 of the strut 93 is made 50 of reduced width and extends through a suitable opening on the mid-line of the frame. The upper end 100 of the strut is made of greater width so that the ends of the halves of the lever 94 will seat in parallel fashion between the upstanding retaining flanges 101. The lever 91 is disposed 55 for the major portion of its length within the cavity of the side frame, suitable openings being provided for its insertion and 60 operation. The lower end of the spring seat 88 also extends within the cavity of the side frame.

Thus when the frames are assembled and the various levers and struts set together in 65 place, it will be seen that the entire outfit

is interlocked without the use of a single bolt or other similar fastening. The springs and bolster then being applied the bolster keepers 102 are riveted fast and the entire truck is held together.

It will be appreciated that the entire load is applied to a truck frame at the point 92. The frame tie member 86 is located in line with this point and the frame is arched about this tie line as a center of action. It 70 will be understood that the frame member 87 is for bolster guiding and brake action forces alone and has no part in the true truss action. The frame is accordingly made deepest at the line of the member 86 and the 75 top and bottom arch members extend in straight lines from here to the points of final reaction.

The invention, an embodiment of which is thus described, provides a most economical 80 and satisfactory method of supporting a railway vehicle. Other embodiments are possible within the scope of the appended 85 claims without departing from the spirit thereof.

What is claimed is,

1. A railway vehicle having a supporting truck at each end, the load being applied to one of the trucks at four points and to the other at three points.

2. A railway vehicle having a supporting truck at each end, the load being applied to the one truck at four points spaced laterally and longitudinally from each other and being applied to the other truck at three 95 points arranged in triangular fashion, one of said points being located substantially on the longitudinal center line of the vehicle.

3. A railway vehicle having a supporting truck at each end, each of which is provided with a plurality of load-receiving seats, there being means provided for equalizing the load among all of said seats of one truck but not of the other truck.

4. A railway vehicle having a swiveling supporting truck at each end, each of which is provided with not less than three load-receiving seats, the same being spaced laterally and longitudinally from each other and away from the axis of swiveling, and rollers disposed in radial lines from the axis of swiveling as a point of origin and interposed between the vehicle body and the said load-receiving seats.

5. A railway vehicle having a supporting truck at each end, each of which is provided with four load-receiving seats, there being a reduced number of load imparting seats on the body of the vehicle, with centrally 115 loaded equalizing means extending between at least two of said seats on the trucks.

6. A railway vehicle having a truck, a transversely disposed equalizer carried by the vehicle body and bearing at its ends 120

- upon the truck, the said equalizer being centrally loaded and being capable of a pivotal movement with respect to the vehicle body.
5. 7. A railway vehicle having a truck, a transversely disposed equalizer carried by the vehicle body and bearing at its ends upon the truck, the said equalizer being centrally loaded and being capable of a 10 pivotal movement with respect to the vehicle body, there being at least one other bearing point of the body upon the same truck.
8. In a railway vehicle having a center 15 sill and a truck, a transversely disposed equalizer carried by the vehicle body and bearing at its ends upon the truck, the said equalizer being arranged to receive loads at its center from the center sill.
20. 9. In a railway vehicle having a center sill and a truck, a transversely disposed equalizer carried by the vehicle body and bearing at its ends upon the truck, the said equalizer being arranged to receive loads 25 at its center from the center sill, and being formed to surround the said center sill.
10. In a railway vehicle having a center sill and a truck, a transversely disposed equalizer carried by the vehicle body and 30 bearing at its ends upon the truck, the said equalizer being arranged to receive loads at its center from the center sill, and having a tie member extending in floating fashion beneath the center sill.
35. 11. In a railway vehicle having a center sill and a truck, a transversely disposed equalizer carried by the vehicle body and bearing at its ends upon the truck, the said equalizer having a pivoted load-receiving 40 bearing upon the center sill and being capable of a slight rotative motion thereabout.
12. A railway car truck having a bolster with a plurality of load-receiving seats and a plurality of load-carrying members, and 45 means connecting the said load-carrying members arranged to admit of a slight relative change in horizontal plane of the said load-receiving seats but at the same time to hold the same in fixed relationship 50 laterally and longitudinally of the truck.
13. A car truck side frame having top and bottom arch members which converge at the ends of the frame and diverge to a maximum at a point mediate the ends, a 55 tie member connecting the arch members at the point of greatest divergence, and means for applying the load to the frame at the point of the said tie member.
14. A car truck side frame of trussed 60 construction having top and bottom arch members which are joined together at the ends of the frame and are in spaced relationship throughout the intermediate portion of the frame, there being a bolster 65 window opening in the said frame, the same being defined at one side by a vertical truss member and at the other side by a guide member, the latter being independent of the truss action in the frame. 70
15. In a car truck, a plurality of side frames and cooperating equalizers and connecting links, the side frames being coupled and the equalizers and links being so arranged and assembled as to interlock and to 75 hold the side frames in coupled relationship.

In testimony whereof I affix my signature.

JOHN A. PILCHER.
